UNITED STATES PATENT OFFICE.

WILLIE L. BEAVERS, OF SPRINGFIELD, MISSOURI.

PRESSER FOOT FOR SEWING MACHINES.

Application filed June 3, 1921. Serial No. 474,637.

To all whom it may concern:

Be it known that I, WILLIE L. BEAVERS, a citizen of the United States, residing at Springfield, in the county of Greene and State of Missouri, have invented a new and useful Presser Foot for Sewing Machines, of which the following is a specification.

This invention relates to sewing machines, and is more particularly directed 10 to a new and improved presser foot which is adapted to be used in cooperation with a sewing machine for guiding and holding down a bottom welt strip to the sole of a shoe when said welt is sewed to the shoe. 15 The invention consists broadly of a presser foot provided with a vertical opening through the foot proper, and in which is adapted to be reciprocated an awl and a needle, and a horizontal opening which 20 is located in the toe of the foot, and is substantially rectangular in shape, which opening is adapted to direct the welt strip into position onto the sole of the boot or shoe, and into the path of the needle and awl, so 25 that as the welt strip receives the sole attaching stitches and is sewed to the sole, the sole is likewise sewed to the upper part of the shoe.

The presser foot is adapted to not only 30 hold the strip when the awl and needle are inserted through the same, but also to guide the strip along the shoe, where it is forced into position on the margin of the sole and into the attaching line as the operation of sewing the sole progresses. The 35 said presser foot serves together with the manipulation of the shoe by the hand of the operator to bend the tread welt sideways without buckling the same, as the sewing proceeds around the bends or 40 grooves, particularly while traveling around the toe, or in making a turn when sewing from the shank to the ball of the sole. A guideway of the presser foot maintains the strip in proper position relatively to the needle and awl.

The presser foot also may be used in plain sewing of the sole without the addition of the welt strip.

50 The invention will be best understood from a consideration of the following detailed description taken in connection with the accompanying drawing forming part of this specification, with the understanding, however, that the invention is not confined to any strict conformity with the

showing in the drawing, but may be changed and modified so long as such changes and modifications mark no material departure from the salient features 60 of the invention as expressed in the appended claims.

In the drawings:—

Fig. 1 is a side elevation of the presser foot secured to the operating arm of a sewing machine, with the shoe shown in dotted lines in front of the presser foot.

Fig. 2 is a front elevation of the presser foot.

Fig. 3 is a vertical section of the presser foot.

Fig. 4 is a view in perspective of the presser foot proceeding towards the toe of a shoe when the shoe is back of the presser foot.

75 In the drawings, 1 designates a work rest or table, 2 an awl, and 3 a needle. A presser foot 4 is secured to the presser bar 5 of the sewing machine by means of screws 6 which are inserted into threaded perforations which are at right angles to each other in the shank 7 of the presser foot. The awl 2 and the needle 3 are operated by the usual sewing machine mechanism for reciprocating these parts. The shank of the presser 85 foot is gradually diminished in size at a point where the shank joins the foot 8.

The foot 8 comprises a toe 9, the straight sided portion 10 having a slightly depressed portion 11 which is adapted to engage the 90 side of the shoe, and a rounded bulging longitudinal side 12. An opening 13 running longitudinally of the foot and extending vertically through the foot is enclosed by the toe 9 and the sides 10 and 12 and the heel 95 14 of the foot. The upper longitudinal edge is cut away or beveled at 15. At the point where the side 12 joins the shank 7, a guideway 16 is formed over which a thread may be drawn. This guideway is finished by 100 polishing or is made exceptionally smooth in order that a thread will not be broken or injured as it passes over this guideway.

The base 17 of the foot 8 is inclined upwardly from the heel to the toe and has side 105 flanges 18 and 19 depending from its periphery, receding rearwardly to the heel and connected together by a front flange 20 depending from the toe of the presser foot, in which is located the horizontal slot 21, and 110 through which is adapted to be inserted and guided by the flanges 18 and 19, a welt 22

which is wound upon the spool 23 secured in any suitable manner to the sewing machine.

A thread 24 which proceeds from a reel rotatably mounted on the machine is directed to the vertical opening 13 in the presser foot, and is adapted to be caught by the needle 3 and pulled through an opening in the welt and the sole of the shoe, which opening was previously made by the awl 2.

10 The operation of my device is as follows: In Fig. 1 the presser foot that guides the welt 22 is shown in position behind a shoe, which is shown in dotted lines. The welt is drawn from the spool 23 through the horizontal slot 21 and guided by means of the flanges 18 and 19 of the presser foot towards the toe of the shoe and along the edge of the sole, while the awl is reciprocated in the vertical opening 13 to perforate the welt 22

15 and the sole in order that the thread 24 may be drawn through the perforations made by the awl and complete the sewing operation.

The presser foot, as is the case in all machines of this kind, is adapted to be reciprocated upwardly and downwardly, and by these movements combined with the feeding of the work serves to force or crowd the welt strip gradually and fully into its proper place on the edge of the sole.

20 30 The awl operates close to that part of the opening which is nearest to the toe of the presser foot. As the presser foot descends onto the work for a new stitch, it carries forwardly with it the welt towards the toe and guides the same in its proper position on the tread of the sole.

What is claimed is:—

1. A pressure foot for guiding welts to be sewed on shoes, comprising a shank, a foot proper divided with a vertical opening with

the bottom of the foot inclined rearwardly from the toe to the heel, a flange depending from the toe and extending rearwardly along the side edges of the bottom of the foot and gradually decreasing in height to a point 45 midway between the heel and toe where the flange merges into the bottom of the foot, the portion of the flange depending from the toe being provided with a horizontal slot for receiving the welt and opening into 50 an inclined guideway for the welt formed by the depending flange and the bottom of the foot, the bottom edge of that portion of the flange depending from the toe being adapted to engage the part of the shoe to 55 be sewed, with the unflanged bottom portion of the foot forcing the welt into engagement with that part of the shoe being sewed.

2. A pressure foot for guiding welts to 60 be sewed on shoes, comprising a shank, a foot proper provided with a vertical opening, with the bottom of the foot inclined rearwardly from the toe to the heel, a flange depending from the toe provided with a 65 horizontal slot to receive and hold the welt, with the bottom edge of the flange resting on that portion of the shoe which is being sewed, while the bottom portion of the foot which is adjacent the heel is adapted to 70 force the welt into engagement with the part of the shoe to which the welt is being applied, the vertical opening in the foot being located between these two engaging portions of the foot.

In testimony, that I claim the foregoing as my own, I have hereto affixed my signature.

WILLIE L. BEAVERS.
